UNITED STATES PATENT OFFICE.

ALLEN BAGLEY, OF YPSILANTI, MICHIGAN.

RAILWAY-JOINT.

SPECIFICATION forming part of Letters Patent No. 416,150, dated December 3, 1889.

Application filed July 24, 1889. Serial No. 318,493. (No model.)

To all whom it may concern:

Be it known that I, ALLEN BAGLEY, a citizen of the United States, residing at Ypsilanti, county of Washtenaw, State of Michigan, have 5 invented a certain new and useful Improvement in a Railway-Joint; and I declare the following to be a full, clear, and exact description of the invention, such as will enable others skilled in the art to which it applies 10 to make and use the same, reference being had to the accompanying drawings, which form a part of this specification.

My invention relates to a new and useful improvement in railway-joints; and it consists 15 of the devices and appliances, their combinations and arrangements, as more fully hereinafter described, and pointed out in the claims, and more clearly illustrated in the accompanying drawings, forming a part of 20 this specification, in which—

Figure 1 is a view in perspective illustrating my invention. Fig. 2 is a vertical cross-section adjacent to the spikes E. Fig. 3 is a vertical section adjacent to the bolts G, and 25 Fig. 4 is a plan view of the adjacent ends of the rails with the bolts G in section.

My invention contemplates the formation 30 of a railway joint of superior firmness, durability, and economy, in which the necessity of punching the ends of the rails and the use of connecting-bolts passed commonly through the rails and fish-plates are entirely dispensed with.

I carry out my invention as follows: 35 A A' represent two railway-rails having their ends adjacent.

B B' denote fish-plates, which are constructed to fit snug up in under the flanges A² of the head or tread of the rail, the lower 40 edge of said plates resting also upon the lower flanges A³ of the rail, respectively, the inner faces of the plates fitting in snugly against the neck A⁴ of the rail, as shown. The rails at their extremities are provided 45 with an underlying bed-plate C, constructed with marginal upturned flanges c c'.

D D' denote key-plates having their outer margins resting against the flanges c c', respectively, of the bed-plate, the inner edges 50 of said key-plates projected against the fish-plates on either side the rails. I prefer to groove the fish-plates longitudinally, as shown

at b, to receive the inner edges of the key-plates. The lower edges of the fish-plates may also be beveled to correspond to the 55 bevel of the lower flange of the rail adjacent thereto. I also prefer to construct the bed-plate C wider than the lower width of the rail, and to permit the engagement of the key-plate between the rail and the bed-plate, 60 as shown at b². The key-plates may each be constructed with a downwardly - extended flange d to fit in between the lower edge of the rail and the flange of the bed-plate adjacent thereto. The bed-plate is also perforated to receive suitable spikes by which it is held in place upon the ties. Thus the spikes E, I prefer to pass through the bed-plate outside the key-plate, the heads of the spikes bearing upon said key-plates to prevent 65 their displacement. At the extremities of the key-plates I prefer also to drive spikes F through the bed-plate into the tie beneath, the spikes F driven in contact with the edges of said key-plates. I prefer also to notch the 70 adjacent flanges of the rail, as shown at a, to engage the spikes in order that the rails may be held thereby from creeping. I also prefer to recess the adjacent ends of the rails at their respective corners, as shown at a', to 75 receive a squared bolt G on either side the rail, said bolts passing through the bed-plate and the corresponding key-plate, the head of the bolt being underneath the bed-plate and held in place by a nut g above the key-plate. 80 These bolts G also serve to prevent the creeping of the rails and in addition serve to 85 strengthen the union of the bed-plate and key-plates. These bolts G, however, may or may not be employed within the scope of my 90 invention.

This joint does away with the bolts and nuts commonly used to unite the fish-plates with the rails, while the joint is every way firm and strong. At the same time it is evident 95 that there is greater durability, and will be far less wear than in fish-joints as ordinarily constructed. It will be observed that the strain when the cars are running over the joint is communicated from the rails, fish-plates, and key-plates to the bed-plate, which is firmly spiked to the rail. The spikes E may be so driven as to draw the key-plates 100 in firmly against the fish-plates.

What I claim as my invention is—

1. In a railway-joint, the combination of the bed-plate, the fish-plates constructed with continuous longitudinal grooves respectively 5 extending from end to end on the outer faces of said fish-plates, a continuous key engaging the bed-plate, and the groove of each of said fish-plates, the construction being such that the key-plates may be engaged in place 10 from the ends of the fish-plates and of the bed-plates, substantially as set forth.

2. In a railway-joint, the combination, with the railway-rails having the adjacent ends of their bases provided with corresponding recesses, of a bed-plate underlying said rails 15 and constructed with marginal flanges, fish-plates located against the neck of the rail and provided with longitudinal grooves, key-

plates having their lower edges located between the edges of the base of the rail and 20 the marginal flanges of the bed-plate and having their upper edges engaged in the grooves of the fish-plates, spikes driven through said base-plate with their heads overlapping the outer edges and the ends of the 25 key-plate, and bolts passing through the base-plate, the recesses in the base of the rail and key-plate, and provided with tightening-nuts, substantially as set forth.

In testimony whereof I sign this specification in the presence of two witnesses.

ALLEN BAGLEY.
